UNITED STATES PATENT OFFICE

RUDOLPH CONRADER, OF ERIE, PENNSYLVANIA.

RELIEF DEVICE FOR COMPRESSORS.

1,239,568.

Patented Sept. 11, 1917.

Specification of Letters Patent. Application filed January 3, 1916. Serial No. 99,733.

To all whom it may concern:

Be it known that I, RUDOLPH CONRADER, a citizen of the United States, residing at Erie, in the county of Erie and State of Pennsylvania, have invented new and useful Improvements in Relief Devices for Compressors, of which the following is a specification.

This invention relates to relief devices and consists in certain improvements in the construction thereof as will be hereinafter fully described and pointed out in the claims.

The invention is illustrated in the accompanying drawings as follows:

Figure 1 shows a side elevation of the compressor cylinder with relief device in place thereon.

Fig. 2 a section on the line 2--2 in Fig. 1. Fig. 1 marks the compressor cylinder, 2 the inlet port, 3 the inlet valve, 4 a spider arranged in the inlet passage through which the stem 5 of the inlet valve extends, and 6 a spring tending to close the inlet valve and being arranged between the spider 4 and the head 7 on the stem 5. The inlet valve seat and its parts are contained in a valve carrier 8 which fits in the opening 1* in the cylinder. The carrier 8 has the cylindrical opening 9 in its rear end in which is arranged a plunger 10. A cap 11 is arranged over the carrier 8, thus forming a closure for the plunger 10 and thus completing with the cylinder 9 a relief valve motor.

A pipe 12 leads from the cap 11 to a cylinder 13. The cylinder 13 is provided with a plunger valve 14. The cylinder has a reduced bottom which extends into an opening 15 in a controlling motor body 16. A closure plug 17 is arranged in the end of the body 16 forming a chamber 18 communicating with the cylinder 13. A passage 19 leads from the chamber 18 and this passage is controlled by a valve 20. The valve 20 is carried by a piston 21, the piston being arranged in a cylinder 22 in the body 16. A pipe 23 leads from the cylinder 22 to the discharge or receiver 24 leading from the compressor. Ordinarily the pipe 23 would lead to a larger receiver than the pipe 24 so as to relieve it of the pulsations of the compressor, the essential feature being that it be connected with the supply of pumped fluid varying in pressure as the pressure of the pumped fluid varies. A push pin 25 is carried against the piston 21 and a rock arm 26. The rock arm 26 is mounted on a pin

27 and forms a bell crank lever with the arm 28. A weight 29 is arranged on the arm 28. A stop arm 30 is provided with an adjusting screw 31 to vary the maximum opening of the valve 20.

The pipes 12, one from each intake valve, lead to opposite sides of the cylinder 13 forming a communication with the cylinder through the openings 35 in the walls of the cylinder. The valve 14 is held in its lower position by a spring 32, the spring being tensioned between the valve and the plug 33 at the upper end of the cylinder. A small leak opening 34 is arranged through the valve 14 and the plug 33 has an opening 33a of sufficient size to take care of any leakage through the leak opening 34.

It will be observed that the weight operating against the piston 21 forms a counter pressure device exerting approximately uniform pressure against the piston so that when the piston begins to move, it moves a sufficient distance ordinarily to open the valve some distance and lets in a sufficient amount of air to positively operate the parts.

The difficulty which has been encountered in this type of device is that with the counter pressure device, when the air pressure reaches a point which in its action on the piston 21 will practically balance the counterpressure of the weight 27 the seating pressure is removed from the valve 20 and in consequence there is, under such circumstances, an unavoidable leakage past the valve 20. This leakage if led direct to the relief device is sufficient to build up a pressure under the plunger 10 that will a little more than balance the spring 6 so that in

the operation of the compressor the valve 3 will be open part of the stroke but when subjected to the high velocity of other parts of the stroke will close. This closing will take place somewhere during the central part of the stroke and the closing due to the high velocity of the air will be very violent thus injuring the valve. In the present invention this difficulty is entirely obviated in that the leak opening 34 is sufficient to take care of this leakage which accompanies the balanced condition. When a sufficient amount of air is delivered to the chamber 18 to start to move the valve 14 which will be incident to an opening by the valve 20 this will be sufficient to immediately lift the valve 14 past the openings 35 so that pressure sufficient to positively actuate the

- piston 10 will be delivered to the relief motor and this pressure will be sufficient to hold the valve open even against a high velocity. When the pressure is again reduced 5 in the receiver, the valve 20 is closed and this permits the valve 14 to close and give a practically instant release to the plunger 10.
- In order to hasten this release where very violent fluctuations are encountered I prefer 10 to provide the openings 36 through the sides of the valve 14. These openings lead into a circumferential groove 36^a and to a discharge opening 13^a so that when the plunger reaches this point in its downward 15 movement the air is immediately discharged from the pipes 12 and the relief valve motors.
- What I claim as new is—
1. In a relief device for compressors, the combination of a compressor cylinder; a relief mechanism on the cylinder; a fluid actuated relief motor actuating said mechanism; a controlling valve for said motor closing and opening by a movement of the valve 20 head toward and from the valve seat; a valve motor for said valve controlled by the pumped fluid from the compressor; a counterpressure device for the valve motor having approximately uniform resistance to the valve motor as the valve opens; and a connection between the controlling valve and the relief motor having a leak sufficient to permit the escape of a leakage incident to a balanced condition of the valve motor.
  2. In a relief device for compressors, the combination of a compressor cylinder; a relief mechanism on the cylinder; a fluid actuated relief motor actuating said mechanism; a controlling valve for said motor; a valve 25 motor for said valve controlled by the pumped fluid from the compressor; a counterpressure device for the valve motor having approximately uniform resistance to the valve motor as the valve opens; a connection between the controlling valve and the relief motor having a leak sufficient to permit the escape of a leakage incident to a balanced condition of the valve motor.
  3. In a relief device for compressors, the combination of a compressor cylinder; a relief mechanism on the cylinder; a fluid actuated relief motor actuating said mechanism; a controlling valve for said motor; a valve 30 motor for said valve controlled by the pumped fluid from the compressor; a counterpressure device for the valve motor having approximately uniform resistance to the valve motor as the valve opens; a connection between the controlling valve and the relief motor having a leak sufficient to permit the escape of a leakage incident to a balanced condition of the valve motor; and an auxiliary valve controlling the connection actuated by the air in the connection; and an auxiliary pressure device for the valve retarding the action of the valve until the pressure in the connection is sufficient to positively actuate the relief motor.
  4. In a relief device for compressors, the combination of a compressor cylinder; a relief mechanism on the cylinder; a fluid actuated relief motor actuating said mechanism; a controlling valve for said motor closing and opening by a movement of the valve 35 head toward and from the valve seat; a valve motor for said valve controlled by the pumped fluid from the compressor; a counterpressure device for the valve motor, having approximately uniform resistance to the valve motor as the valve opens; a connection between the controlling valve and the relief motor having a leak sufficient to permit the escape of a leakage incident to a balanced condition of the valve motor; a cylindrical valve controlling said connection actuated by the air in the connection, 40 said cylindrical valve having an intermediate passage arranged in the walls thereof to hasten the release of the air from said connection; and an auxiliary pressure device for the valve retarding the action of the valve until the pressure in the connection is sufficient to positively actuate the relief motor.
  5. In a relief device for compressors, the combination of a compressor cylinder; a relief mechanism on the cylinder; a fluid actuated relief motor actuating said mechanism; a controlling valve for said motor closing and opening by a movement of the valve 45 head toward and from the valve seat; a valve motor for said valve controlled by the pumped fluid from the compressor; a counterpressure device for the valve motor, said controlling valve and counterpressure device being relatively arranged to give an abrupt opening to the valve when the valve motor is actuated; and a connection between the controlling valve and the relief motor having a leak sufficient to permit the escape of a leakage incident to a balanced condition of the valve motor.

In testimony whereof, I hereunto set my hand.

RUDOLPH CONRADER.
